UNITED STATES PATENT OFFICE.

TELESPHORE J. BEAUDETTE, OF LOS ANGELES, CALIFORNIA.

PUMP-GOVERNOR.

960,249.

Specification of Letters Patent. Patented June 7, 1910.

Application filed June 2, 1909. Serial No. 499,777.

To all whom it may concern:

Be it known that I, TELESPHORE J. BEAUDETTE, a citizen of the United States, residing in the city of Los Angeles, county of Los Angeles, and State of California, have invented new and useful Improvements in Pump-Governors, of which the following is a specification.

My invention relates to an electrically operated governor for controlling the action of a number of pumps which are used with irregular power such as a wave motor, and the object thereof is to equip the pumps with an electrically operated regulator which will automatically throw into or out of operation one or more pumps as the power increases or decreases. I accomplish this object by the mechanism described herein and illustrated in the accompanying drawings, in which—

Figure 1 is a side elevation partly in section and partly broken away and partly diagrammatic showing a pumping plant with three pumps, with the pump operating means omitted. Fig. 2 is an elevation of the pumps on a plane at right angles to that of Fig. 1 with the lower portion in section. Fig. 3 is an enlarged detail view of the governor controlling the electrical circuits. Fig. 4 is an enlarged fragment of one of the pump piston stems with the lower portion thereof partly in section. Fig. 5 is an enlarged view of the upper end of the lower portion of the plunger piston stem and of the connection sheath attached to the top of the pump cylinder. Fig. 6 is a top plan of the parts shown in Fig. 4. Fig. 7 is a diagrammatic representation of the electrical apparatus forming a part of the pump controlling mechanism.

In the description of my apparatus I shall describe it as applied to operate a battery of pumps which are operated by wave motors, not shown. In the drawings I have shown three pumps but the number can be extended to as many pumps as may be desired to be operated by one wave motor unit.

In the drawings 10 is a wharf structure upon which are mounted pumps 11, 12, and 13, all of the same construction and all are operated by a common power shaft 14 provided with power pulley 15 to which power is applied from a wave motor, not shown. The power shaft is provided with cranks 16, 17 and 18, there being a crank for each pump. As all of the pumps are similarly

constructed I will describe only one pump. Each pump is provided with a pump barrel 19 which is provided with an admission port 20 connected to the suction pipe 21. This connection is controlled by a check valve 22. On the other side of the pump barrel is the discharge port 23 which is connected to the discharge pipe 24 which leads the water to a place of use or storage not shown.

The discharge pipe is provided with an air chamber 25 of usual construction to prevent pounding. In the pump barrel is a plunger or piston 26 of ordinary construction. This piston is provided with a stem the upper section 27^a of which is connected to the cross head 28. Intermediate the piston and the cross head the stem is divided and the upper portion thereof 27^a is provided with a conical head 29 which is received in a conical socket 30 in the head 31 of the lower portion 27^b. Head 31 is provided with vertical grooves 32 and 33 in which grooves are pivotally mounted clutch bars 34 and 35 which are provided with heads 34^a and 35^a which when the stem is in its operative position as best shown in Fig. 4, engage the head 29 of section 27^a and lock the two sections together. Head 31 is provided with a transverse aperture 36 in which is mounted the double solenoid magnet 37 having plungers 38 and 39. Plunger 38 is pivotally connected to clutch bar 34 and plunger 39 is pivotally connected to clutch bar 35. When the solenoid magnet is energized it draws the clutch bars to the position shown in Fig. 4 and holds them in that position. Head 31 is provided with sockets 40 and 41 in which are mounted spiral springs 42 and 43 which bear against clutch bars 34 and 35 and force them outwardly whenever the solenoid is de-energized. These springs are not strong enough to disengage the clutch bars on the upward movement of the stem, owing to the friction between the parts. Stops 44 and 45 are secured to head 31 to limit the outward movement of the free ends of the clutch bars. These stops permit the free ends of the clutch bars to move outwardly just far enough so that the heads thereof will be out of the path of movement of the head of the upper section 27^a. Head 31 has secured thereto a contact spring 46 which is insulated from said head by insulation 47. One pole of the solenoid magnet is connected by an insulated wire 48 with the contact spring 46.

49 is a guide secured upon the top of the pump barrel and guides the piston stem 27. Upon the top of guide 49 is secured an insulated washer 50 to which washer is secured 5 contact cup 51 the upper end of which flares outwardly. Contact cup 51 is engaged by contact spring 46 at the lower movement of the piston stem. Each pump is provided with a contact cup 51, and each of these cups is 10 connected by a line wire to the back board 52 of the switch board. This switch board is also provided with a front board 53 and the two boards are separated and adapted to be electrically connected by plugs in the 15 usual well known manner inserted in holes which register in the two boards. In the diagram the solenoid of pump 11 is connected by line 55 with the vertical line of holes 54^a. The solenoid of pump 12 is connected 20 by line 56 with the vertical line of holes 54^b. The solenoid of pump 13 is connected by line 57 with the vertical line of holes 54^c. The other poles of the solenoids are connected by a common line 58 to a source of electrical 25 energy here shown as a dynamo 59. The other pole of the dynamo is connected by line wire 60 to contact 61. Adjacent to contact 61 are contacts 62, 63 and 64. Contact 62 is connected by line 65 with a horizontal 30 row of holes 66^a. Contact 63 is connected by line 67 with the horizontal row of holes 66^b, contact 64 is connected by line 68 by a horizontal row of holes 66^c. These lines of 35 holes on the front board register with the holes of the back board so that contact 62 for illustration may be connected through the switch board with the solenoid of any of the pumps.

69 is the rotating shaft of an ordinary ball governor to which is affixed the operating pulley 70. A belt 71 passes around this pulley and around pulley 72 which last pulley is mounted upon shaft 14 by means of which the governor is operated. A sleeve 73 is connected to the sliding head 74 of the ball governor and is slidably mounted upon the governor shaft 69. Sleeve 73 has secured thereto a contact sleeve 75 which is insulated from the governor sleeve by insulation 76 as best shown in Fig. 3. Pitmen 77 connect the cross heads to the shaft 14.

In the operation of my governor we will assume that pulley 15 is connected up to the wave motor. As the shaft begins to revolve, the ball governor draws contact sleeve 75 into engagement, first with contact 62 and then with contact 63 and then with contact 64. Now if plugs are inserted in the proper holes in the switch board, as the contact sleeve is moved forward the solenoid of pump 11 will be first energized, then the solenoid of pump 12 and then the solenoid of pump 13, so that as shaft 14 is rotated pump 11 will be put into action, and then pump 12, and then pump 13. Should any

pump become disabled, by removing the proper plug from the switch board such pump may be cut out without affecting the action of the other pumps and the same can be repaired. It will be observed that when 70 the wave action falls below the power to operate all the pumps in a unit that the pumps are successively and automatically cut out by the action of the governor, and as the wave power increases they are successively and automatically thrown into action. By the use of the switch board the pumps can be thrown into action in whatever order desired.

Having described my invention what I 80 claim is:

1. A pump governor comprising a divided plunger stem; clutch members carried by one portion of the divided stem adapted to engage the other portion of the stem and 85 lock the two parts together; electrically operated means for bringing the clutches into engagement with the other member of the stem when the circuit of said electrical means is closed; mechanical means for closing or opening the circuit of the electrical means, said mechanical means being operated by the power shaft of the pump.

2. In a pump governor a divided plunger stem; electrically operated means for locking the two parts of the plunger stem together; and mechanical means controlled by the motion of the power shaft of the pump controlling said electrical means, whereby the electrically operated means are rendered 100 active or inert.

3. In a plurality of pumps operated by irregularly applied power, a governor for said pumps, comprising divided plunger stems, one portion of the plunger stems being provided with heads and the other portion of the plunger stems being provided with sockets and carrying pivoted clutches adapted to engage the heads of the other members and lock the parts of the plunger 105 stems together; electrically operated means adapted to cause the clutches to lock the parts of the plunger stems together when said means are energized; mechanical means adapted to disengage the clutches when the 110 electrically operated means are deenergized; mechanically operated means for opening and closing the circuits of the electrically operated means, whereby the plunger stems are locked or unlocked as the circuits are 115 closed or opened.

4. In a plurality of pumps operated by irregularly applied power; a governor for said pumps, comprising divided plunger stems, one portion of the plunger stems being provided with heads and the other portion of the plunger stems being provided with sockets and carrying pivoted clutches adapted to engage the heads of the other members and lock the parts of the plunger 125 130

stems together; a magnet for each of said stems, operatively connected to said clutches; a source of electrical energy; connections from said source of electrical energy to said 5 magnets; a connection from said source of energy to a stationary contact; other stationary contacts adjacent to said first contact; connections from said last contacts to different magnets on the plunger stems; a 10 sliding contact adapted to connect two or more of said stationary contacts and thereby close the circuit or circuits of one or more of the magnets; and mechanical means operated by the power shaft of the pump to cause said sliding contact to connect or disconnect said stationary contacts.

In witness that I claim the foregoing I have hereunto subscribed my name this 28th day of May, 1909.
